MULTIPLE CONNECTION

Lee M. Seaver, Kokomo, Ind.

Application November 3, 1945, Serial No. 626,500

5 Claims. (Cl. 173—334)

1

This invention relates to electrical connection sockets and plugs.

It is an object of the present invention to provide a wall or similar socket for electrical cord connections which is adapted to normally reside in a position substantially flush with the wall with which it is associated, and which embodies means such as may be manually and optionally positioned to protrude from the wall in a manner to provide for the attachment thereto of a plurality of electrical cord plugs or similar connectors.

Another object of the invention is to provide, in a device of the character set forth, an improved sliding means of a projectable and retractable type whereby it may be positioned to extend and project from the wall and receive a plurality of cord plugs or similar connectors, and which will maintain, while in such varying positions, effective contact with the source of supply of electrical energy.

A further object of the invention is to provide a slidable device of the character set forth which may, in withdrawn position, receive an electrical cord connecting plug member, and which, when in extended position, may receive, in addition, a plurality of such plugs or equivalent appliances.

Other objects and features of the present invention relate to the combination and interrelation of parts, whereby the whole forms a neat, attractive and efficient appliance of the class described, and one which may be receivable within a wall when not in use.

These and other objects, features and advantages of the present invention will be apparent from a consideration of the following specification taken in connection with the drawings, in which—

Figure 1 is a face or end elevational view of the preferred embodiment of the present invention.

Figure 2 is a cross-sectional view taken on line 2—2 of Figure 4.

Figure 3 is a longitudinal vertical section taken on the plane of the irregular central line 3—3 of Figure 1.

Figure 4 is a horizontal sectional view at right angles to Figure 3 taken on the line 4—4 of Figure 3.

Referring more particularly to the drawings, my invention includes an escutcheon plate 10 which is adapted to marginally frame and partially cover an aperture 11 in a wall 12 to which it may be readily secured, in any desired manner. The plate 10 is centrally apertured as at 14, the aperture being preferably square or of other con-

2

figuration such as is adapted to conform with the configuration of the projectable and retractable electrical contact unit or means 15, the structural details of which will be hereinafter described.

Mounted within the aperture 11, a casing is provided including an outer cylinder or casing 16 adapted to fit into said aperture 11; and an inner, rectangular receptacle 17 provided at its inner closed end 18 with electrical connecting terminals 19. The inner and outer parts or complementary sections 16 and 17 of the casing are webbed together and attached at their outer ends and, by way of fastenings 20, to the escutcheon plate 10. The opposed flat walls of receptacle section 17 are provided with elongated slots 21 through which projecting lugs 22 are adapted to move in and out, said lugs being carried by a sliding current feeder contact-receiving part 23 movable with and guided by the receptacle 17.

The part 23 of unit 15 is in the form of a tubular shell from which the projecting members 22 extend through the slots 21, as hereinbefore described. Within shell 23, a longitudinally extending insulated shaft 24 is provided, and this is secured by a fastening screw 25 to the spider 26 carried by the inner end portion of said shell. Mounted upon shaft 24 adjacent the front end thereof, there is provided a plurality of contact fingers 27 which are illustrated in the form of substantially U-shaped members, the legs of which are adapted to engage each other under spring tension, and to receive therebetween inserted contact prongs carried by regulation cord and appliance plugs, as illustrated at 28.

It will be understood that the contact fingers 27 are arranged in pairs, one member of each pair being connected with the opposite electrical polarity through suitable connection with the members 19. Suitable side T-slots 29 are provided in the receptacle 23 in alignment with the fingers 27, whereby the variable types of prongs carried by the plugs 28 may be received therethrough and entered between the fingers 27. The insulated shaft 24 is adapted to terminate in an adapter head 30 which is enlarged and adapted to carry a pair of outstanding fingers 27a. The end cap 31 is associated with the shell 23 and is suitably apertured, as at 32, for cooperated admittance of contacting pins with the members 27 carried by the head 30. The end cap 31 is preferably recessed, as at 33, to form a finger grip 33a for controlling sliding movement of the entire unit 15 with respect to the relatively fixed sections 16 and 17.

For completing the electrical circuit, between the connection members or binding posts 19 and the clip members 21, said members 19 are provided with outwardly extending contact arms 34 which embrace opposite sides of the insulator 24 and which are thus adapted to accommodate arms 35, one of which is adapted for electrical connection with one of each of the pairs of contact receiving clip members 27, while the other is adapted for electrical connection with the other one of each pair of said contact receiving clip members 27, as clearly shown in Figure 4 of the drawings.

By referring to Figures 3 and 4 of the drawings, the operation of the device will be readily understood. In the inward or retracted position of the structure as shown in Figure 4, the endmost, outstanding contact receiving members 27a may receive suitable contacting prongs carried by the plug 28 and thus electrical contact will be established through the interconnected conductors and will energize the appliance (not shown) associated with the plug 28. When a plurality of plugs are desired for use in connection with the device, the casing 23, unit 15, including is slid outwardly from the receptacle 17 by the provision of the recessed portion 33 and finger-grip 33a.

In the opposite position, contact is maintained between the arms 34 and contact fingers 35 by the elongation of the arms 34 over which the fingers 35 slide in wiping contact. The proper alignment of the device after movement is maintained and the relative movement is controlled by the provision of the projecting pins 22 within the slots 21. Upon outward position of the device, as illustrated by dotted lines of Figure 3, extra cord plugs 28 may be inserted through the apertures 29 of the casing 23 and their conducting prongs may be received by the contact-receiving members 27 associated with said apertures.

Thus, it may be readily seen that my invention provides for the use of a plurality of cord plug accommodating and connecting members in combination with a single wall-type multiple purpose outlet. It will be seen also that when but a single cord-plug is to be accommodated, the means 15 is then retracted within the wall and is positioned substantially flush therewith, while it may be readily projected for attachment thereto of a plurality of cord-plugs.

Novelty is predicated on and centers around the multiple cord plug accommodating adapter or unit which is normally concealed, confined, and therefore housed in the relatively fixed elongated receptacle 17, the latter mounted in the cylindrical outer jacket or casing 16, said unit 15 being susceptible of readily taking the projected position seen in dotted lines in Figure 3. The arrangement is characterized by simplicity, accessibility, and the outstanding features and advantages are easy to "spot" and identify. Each complements the other. The structure, as a whole, is destined to earn recognition as a real convenience and time saver.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. A multiple-purpose cord connecting outlet of the class described, comprising a receptacle having means whereby same may be fixedly mounted on a wall, floor or the like, said receptacle being provided interiorly with longitudinally extending current delivering arms and coating means for connection with a source of electrical current, a shell telescopically mounted for sliding in said receptacle, said shell being slidably keyed to said receptacle, an adapter shaft mounted longitudinally and centrally in said shell, said shaft being provided with a multiplicity of selectively usable contact clips, said clips being adapted to accommodate prongs on cord plugs and the like, said shaft being provided with longitudinally extending contact fingers, said contact fingers having slidable resilient contact with said arms.
- 5 2. A wall and floor type outlet for supplying current from a source to cord-plugs for use in connection with floor lamps and the like, comprising a longitudinally elongated receptacle adapted to be fixedly mounted, said receptacle being closed at its inner end and open at its outer end, opposed side walls of said receptacle being provided with guide and assembling slots, a hollow elongated shell fitted snugly and telescopically within the confines of said receptacle, said shell being projectible and retractible in relation to the open outer end of said receptacle, said shell being provided with lugs and said lugs fitting slidably in said slots, a pair of longitudinally elongated resilient contact arms secured at one end to an adjacent end of said receptacle, a shaft mounted in said shell and provided with a plurality of sets of selectively usable contact accommodation clips, and a pair of current take-off fingers in electrical connection with said clips, 10 said fingers having sliding contact with said contact arms.
- 15 3. As a new article of manufacture, and as a component part of a structure of the class described, an elongated substantially rectangular receptacle, said receptacle being open at its outer end and closed at its inner end, the last named end being provided with elongated resilient contact arms, said arms projecting into the interior of the receptacle, means for supplying current 20 to the current intake ends of said arms, opposed walls of said receptacle being provided with guide and assembling slots, a cylindrical casing elongated and commensurate in length with said receptacle and surrounding the receptacle and 25 joined to the outer open end of the receptacle by an annular connecting web, and an escutcheon plate fastened to said web.
- 30 4. As a new article of manufacture, and as a component part of an outlet of the class described, an elongated shell substantially rectangular in cross-sectional form and provided at its outer end with a closing cap having a central depression and a cross-pin forming a finger-grip, said finger-grip being located in said depression, 35 said shell being provided interiorly with an axially extending shaft, said shaft being of insulation material and being provided on one end portion with a multiplicity of selectively usable sets of contact accommodation clips and being further provided with longitudinal resilient contact fingers.
- 40 5. A multiple-purpose cord connecting outlet comprising a receptacle adapted to be fixedly mounted on a wall, or the like, said receptacle being provided with current pick-up and deliver-

ing arms and further provided with means to supply current to said arms from a conventional electric source, a current feeder unit telescopically mounted in said receptacle, an adapter shaft mounted longitudinally in said unit, said shaft being provided with a multiplicity of selectively usable contact clips, said clips being adapted to accommodate prongs on cord plugs and the like, said shaft being provided with longitudinally extending contact fingers, said contact fingers having slidable resilient contact with said arms. 10
